PROCESS AND APPARATUS FOR THE PRODUCTION OF
RELIEF IMAGES ON CINEMATOGRAPH FILM STRIPS

Original Filed March 27, 1927

UNITED STATES PATENT OFFICE

JOHN EDWARD THORNTON, OF JERSEY, CHANNEL ISLANDS, ASSIGNOR TO JOHN OWDEN O'BRIEN, OF MANCHESTER, ENGLAND

PROCESS AND APPARATUS FOR THE PRODUCTION OF RELIEF IMAGES ON CINEMATOGRAPH-FILM STRIPS

Original application filed March 27, 1927, Serial No. 174,945, and in Canada March 17, 1927. Divided and this application filed March 22, 1928. Serial No. 263,853.

I have filed an application for this invention in Canada on March 17, 1927.

The present application is a division of Serial No. 174,945, filed March 27, 1927.

5 This invention relates to a process for automatically developing a series of colloid relief-images upon a sensitized continuous film-strip which has been exposed and printed, and for treating and finishing the film-strip, and for removing a temporary reinforcing paper from the film-strip after the images have been developed, and also to apparatus for carrying out the process as a continuous one, the exposed and printed 10 film entering at one end of the apparatus and the dried film-strip with the developed and treated images thereon emerging at the other end of the apparatus.

20 A feature of the invention is that while the process of producing a series of colloid images in relief upon a continuous film-strip is carried out as a continuous and automatic process, it is effected by successive stages or steps, which follow each other and are carried out by separate units of the complete 25 apparatus through which the film-strip passes in succession.

The first step consists in passing the film-strip through a hot water bath to loosen and 30 dissolve the unexposed and soluble portion of the colloid.

Although it is quite possible for this first bath to dissolve the whole of the soluble colloid, the hot water therein would be more 35 or less contaminated by the large quantity of dissolved colloid, and where this colloid is of the colored or dyed variety for producing ready-colored relief images without a subsequent dyeing process, the volume of 40 dissolved colloid and dye accumulating in the first bath would prove a great objection by preventing the production of a sufficiently clean product in one bath.

In the second step the film-strip is therefore 45 passed through a second bath of hot water, or is subjected to the action of hot water sprays, for the purpose of completing the development by removing any remaining soluble colloid from the relief images; and thus by this second step the film-strip is

made sufficiently clean and its images so completely developed that it can be used without further treatment. But should it be found necessary or desirable the film strip may be passed through three or even more baths. 55

At a third step of the process, and in order to modify and improve the quality of the colloid relief images, it is desirable to treat the film-strip with a hardening solution such as chrome-alum, formaline, or other suitable 60 hardening agent. Whilst such treatment may if desired terminate the third stage of the process, the colloid would be hard and brittle and would tend to split away from the celluloid support, and it is therefore advisable 65 to counteract such tendency by treating the colloid with a dilute solution of glycerine, syrup or sugar and water to render the colloid sufficiently flexible and prevent its extreme contraction in drying. 70

The hardening solution and the flexing solution may be applied separately, or they may be mixed and applied simultaneously in a single bath, or by spraying them on to the colloid surface. 75

When the film strip is provided with a temporary reinforcing strip of paper, the paper is loosened from the film-strip during its passage through the hot bath and can be removed by suitable means upon emerging 80 therefrom.

The accompanying drawings show diagrammatically suitable apparatus for carrying out the process according to the invention. 85

In this drawing the developing apparatus comprises two tanks or baths A and B to which hot water is supplied by pump C and removed by the pump D. The supply pump C is connected to the top of the tank A by the pipe c and to the top of the tank B by the pipe c¹, and the exhaust pump D is connected to the bottom of the tank A by the pipe d and to the bottom of the tank B by the pipe d¹. 90

The tank A is provided with a series of upper rollers a arranged in pairs between which the film E passes and a series of lower rollers a¹, the top rollers a being driven and the bottom rollers a¹ being idle. The tank 95 100

B is also provided with a series of upper rollers b arranged in pairs and a series of lower rollers b' , the upper rollers b being driven and the lower rollers b' being idle.

5 A guide roller A^1 is arranged at the inlet end of the tank A to guide the continuous film-strip E to the first pair of rollers a and a pair of reels or rollers A^2 , are arranged above the point where the film-strip E emerges from the tank A, which reels or rollers serve to draw away the temporary reinforcing paper strip E^1 from the film-strip E, the cement attaching the reinforcing paper to the film having been softened 10 during the passage through the tank A. A guide roller A^3 is arranged above the winding rollers A^2 , the film-strip E stripped of its reinforcement passing over this roller before passing to the guide roller B^1 at the 15 film entrance of the tank B.

A number of powerful sprays B^2 are arranged over the top rollers b of the tank B to act on the film-strip E as it passes over each top roller and assist in loosening and 20 dislodging colloid from the depressed parts of the relief images therein. The sprays B^2 are fed with hot water from the pump C through the pipe c^2 which is connected to the pipe c^1 .

30 Although the apparatus is shown in the drawings with two developing baths A and B, additional baths may be employed if desired.

A guide roller B^3 is arranged at the end 35 of the tank B from which the completely developed film strip E emerges, and the film strip E may then pass from this roller B^3 to any desired drying, winding or other apparatus. In the drawings the film E after 40 leaving the tank B is shown as being passed vertically between a pair of sprays F; the sprays F are fed by a pump G to apply a combined finishing or varnishing solution containing hardening and flexing agents to 45 the surface of the film or separate solutions of each applied successively. The surplus solution runs down into the tank H and is re-circulated by the pump G. The film E after being passed between the finishing 50 sprays F passes between a pair of squeezing rollers F^1 to cause the finishing solution to be evenly spread over the film. Other solvents may be used instead of hot water if preferred such as cold solution of bichromate 55 or an acid such as acetic, such alternative solvents being already known but less convenient than hot water. The process and apparatus remain the same if such other solvents are used.

60 What I claim as my invention and desire to protect by Letters Patent is:—

1. A process for producing a series of colloid relief images upon a continuous film-strip, carried out as a continuous and automatic process, consisting in applying a sol-

vent in a plurality of stages, the first stage removing most of the soluble colloid from the film-strip, and the next stage removing the remainder of the soluble colloid left on the film-strip after the first stage.

2. A process for producing a series of colloid relief images upon a continuous film-strip comprising a plurality of stages of treatment of an exposed and printed colloid film-strip by means of a solvent applied by a plurality of baths and spraying devices by which all soluble colloid is removed from the film-strip and any temporary reinforcing strip of paper is loosened, detached and removed from the film-strip, leaving a series 70 of relief images of insoluble colloid upon the film-strip. 75

3. A process for producing a series of colloid relief images upon a continuous film-strip carried out as a continuous and automatic process consisting in applying a solvent in a plurality of stages, the first stage removing most of the soluble colloid from the film strip, and the next stage removing the remainder of the soluble colloid left on the film-strip after the first stage, and subsequently treating with a hardening agent to harden the insoluble colloid relief images. 80

4. A process for producing a series of colloid relief images upon a continuous film-strip carried out as a continuous and automatic process, consisting in applying a solvent in a plurality of stages, the first stage removing most of the soluble colloid from the film strip, and the next stage removing the remainder of the soluble colloid left on the film-strip after the first stage, subsequently treating with a hardening agent to harden the insoluble colloid relief images and finally treating with a flexing agent to render 90 the hardened colloid of the relief images flexible. 100

5. A process for producing a series of colloid relief images upon a continuous film-strip carried out as a continuous and automatic process, consisting in applying a solvent in a plurality of stages, the first stage removing most of the soluble colloid from the film-strip, and the next stage removing the remainder of the soluble colloid left on the film strip after the first stage, subsequently treating with a hardening agent to harden the insoluble colloid relief images, treating with a flexing agent to render the hardened colloid of the relief images flexible, and finally completing the process by drying the film. 110

6. Apparatus for carrying out the process for the development of relief-images in stages upon a continuous film-strip, comprising two tanks through which a solvent is circulated, each of which is provided with a series of rollers at the top and bottom around which the film passes, a pair of reels or rollers arranged between the two tanks, and a series 120 125 130

of sprays arranged over the top rollers of the second tank to act on the film as it passes over each top roller thereof, pumps to circulate the solvents through the tanks, and a series of sprays to act on the film after leaving the second tank to apply a finishing solution to the developed relief images.

5 In testimony whereof I have hereunto set my hand.

10 JOHN EDWARD THORNTON.
